UNITED STATES PATENT OFFICE.

MARIE CASSEL, OF PHILADELPHIA, PENNSYLVANIA.

DESIGN FOR A CAKE-FORM.

51,750.

Specification for Design.

Patented Feb. 12, 1918.

Application filed November 7, 1917. Serial No. 200,830. Term of patent 7 years.

To all whom it may concern:

Be it known that I, MARIE CASSEL, a citizen of the United States, residing at Philadelphia, in the county of Philadelphia and State of Pennsylvania, have invented a new and original and ornamental Design for Cake-Form, of which the following is a specification, reference being had to the accompanying drawing, forming a part thereof.

The figure is a perspective view of a cake form illustrating my new design.

I claim:—

The ornamental design for cake form as shown.

MARIE CASSEL.

Witnesses:

F. A. HOSTER,
AMY B. HORN.
